UNITED STATES PATENT OFFICE.

CYRIL EUSTACE SAYER, OF PURLEY, ENGLAND.

CONDENSING SYSTEM FOR LOCOMOTIVES.

1,426,113.

Specification of Letters Patent. Patented Aug. 15, 1922.

Application filed July 22, 1918. Serial No. 246,102.

To all whom it may concern:

Be it known that I, CYRIL EUSTACE SAYER, a subject of the King of Great Britain, residing at 80 Foxley Lane, Purley, Surrey, 5 England, have invented new and useful Improvements in Condensing Systems for Locomotives (for which I have filed an application in England April 20, 1917, Patent Number 110,306), of which the following is

10 a specification.

This invention relates to condensing systems for steam locomotives of either simple or compound expansion and has for its object the provision of improved means for 15 continuously cooling the circulating water utilized for condensing purposes and so ensuring the maintenance of as good a vacuum as possible.

In the accompanying drawing—

20 Figure 1 is a sectional side view of a locomotive and tender provided with a condensing system embodying the invention.

Figure 2 is a sectional rear view of the tender, and

25 Figure 3 is a front view of the locomotive.

According to the invention I make use of a water cooler *a* arranged in the tender *b* of the locomotive *c*, the said cooler consisting of a spiral coil comprising a large number 30 of turns of sheet-metal. This coil *a* is continuously revolved, by means of a belt *d* from one of the axles of the tender and its lower part is immersed in the water *e* which is to be cooled.

35 Owing to the motion of the locomotive the necessary flow of air through the cooling apparatus may be induced naturally, suitable inlet and outlet ducts *f* and *g* respectively being arranged for this purpose.

40 The condenser *h* is divided into two separate sections arranged in a convenient position one at each side of the engine *c* preferably above the fore part of the foot-plate at the side of the smoke-box so as to clear the

45 driving wheels and to provide the shortest possible path through the pipes *h*¹ for the exhaust steam from the cylinders into the condenser.

In order to prevent the transfer of heat 50 from the smoke-box to the condenser casings and the impairment of the condenser efficiency which would result from the same I propose to introduce between the wall of the smoke-box and the condenser casings a 55 heat insulator consisting of a thickness of suitable non-conducting material *i*.

The circulation of the cooling water between the condenser *h* and the cooling apparatus *a* is effected through the flow and return pipes *j* and *k* by means of the circulating pump of centrifugal type *l* the spindle *l*¹ of which is preferably driven from one of the locomotive axles by the belt *m*.

60 I am aware that by the condensation of the exhaust the forced draught obtained by means of the exhaust blast-pipe will be lost. To overcome this I propose to employ a fan *n* arranged to discharge air to a nozzle *o* situated in the smoke-box and to induce the draught by this means in a similar manner 65 to the exhaust blast. This arrangement would not require the passing of the hot gases from the furnace through the blast-fan which would be situated in some convenient position, preferably at the front of 70 the locomotive and operate by the spindle *l*¹.

75 Steam driven reciprocating vacuum pumps of wet type are employed, such pumps comprising two units *p* each serving one section of the condenser.

80 I also propose to arrange an escape pipe *r* from each pipe *h*¹ to the air blast-pipe *o* for the exhaust steam from each cylinder under the control of an automatic relief valve *s* as usually fitted in conjunction with condensing steam engines, or alternatively under the control of the driver, in the latter case a water sealed relief-valve being fitted at 85 the top of the condenser. With this arrangement the failure of any portion of the proposed condensing system would not involve the stoppage of the engine, which would continue to operate non-condensing, the reservoir of water forming part of the cooling 90 apparatus in the tender being then utilized for feed purposes, not being required under these conditions for circulating through the condenser.

95 By the use of this apparatus it will be 100 possible to cool continuously from the condenser outlet temperature to some suitable lower temperature a sufficient quantity of circulating water to maintain a satisfactory vacuum in the condenser.

105 Claims.

1. In a condensing system for locomotives, the combination with the condenser of a water cooler comprising a closed chamber the sides and ends of which are formed by 110 the sides and ends of the tender, inlet and outlet openings in the said ends for the pas-

sage of air through the chamber and a cylindrical drum formed of many turns of sheet metal rotating with its lower part immersed in the water to be cooled and which 5 water is contained in the lower part of the said chamber.

2. A condensing system for locomotives comprising a condenser, a water cooler consisting of a drum composed of a plurality 10 of turns of sheet metal, dipping into the water to be cooled, means for rotating the

drum, means for inducing an air draught through the cooling apparatus, a centrifugal water circulating pump, and a blast fan external to the locomotive smoke-box, driven 15 from the axle, the fan delivering air only to a blast pipe in the smoke-box in order to induce the necessary blast through the furnace and tubes, substantially as hereinbefore described.

CYRIL EUSTACE SAYER.
